THROTTLE CHECK VALVE

Benjamin C. Benjamin, Flint, Mich., assignor to Fuller & Emerson Manufacturing Company, Detroit, Mich., a corporation of Michigan

Filed Oct. 18, 1965, Ser. No. 497,199
14 Claims. (Cl. 267—1)

ABSTRACT OF THE DISCLOSURE

The throttle check valve disclosed herein comprises a casing including a diaphragm dividing the casing into two chambers. The casing has an opening in one wall communicating with one chamber and a spring is positioned in the one chamber and acts on the diaphragm to yieldingly urge the diaphragm away from the opening. A shaft is fastened to the diaphragm and extends through the other chamber in a wall of the casing and has an opening therethrough providing communication between the end of the shaft and the first-mentioned chamber. The shaft has a valve seat on the end thereof and a cap is provided surrounding the end of the shaft and has a seal adapted to engage the valve seat. A spring yieldingly urges the cap away from the seat and interengaging means between the cap and the shaft limit the axial outward movement of the cap due to the action of the spring.

This invention relates to valves and particularly to valves for checking or retarding the movement of the throttle of a carburetor on an engine of an automotive vehicle to a closed position.

It has long been known that in automotive vehicles having high compression engines, a sudden closing of the throttle after a sudden acceleration results generally in stalling of the engine. Accordingly, it has been heretofore suggested to provide means for retarding the return of the throttle by a check valve that is connected to vacuum and is operable upon lifting the foot from the throttle pedal to provide a retarding force on the return of the throttle to closed position.

It is an object of this invention to provide a throttle check valve that is particularly adapted for use in retarding the return of a throttle to closed position which is effectively protected against dirt and the like and which is low in cost.

In the drawings:

FIG. 1 is a partly diagrammatic side view of a valve embodying the invention.

FIG. 2 is a longitudinal sectional view through the valve shown in FIG. 1.

FIG. 3 is a fragmentary view of a portion of the valve shown in FIGS. 1 and 2, showing the parts in a different operative position.

FIG. 4 is an end view of a cap utilized in the valve.

Referring to FIG. 1, the valve 10 embodying the invention is adapted to be utilized in connection with a throttle linkage that includes a lever 11 which moves with the throttle valve on an engine of an automotive vehicle. In accordance with conventional linkage of a throttle, the lever 11 moves from the solid line position shown in FIG. 1 to the dotted line position when the operator lifts

2

his foot off the throttle pedal. At the same time, the throttle is returning to a closed position.

As shown in FIG. 1, the valve 10 is adapted to be mounted on a bracket 12 and is connected by a flexible line 13 to vacuum from the intake manifold.

Referring to FIG. 2, the valve 10 comprises a casing 14 consisting of two sheet metal halves 15, 16 having peripheral flanges 17, 18 between which a diaphragm 19 is interposed. The flange 17 of the casing half 15 is bent over as at 20 to clamp the diaphragm in position and provide two chambers 21, 22.

The casing half 16 is provided with an orifice 23 that in turn provides communication to the interior of a tubular fitting 24 which is welded on the casing half 16 and onto which the tubing 13 is mounted.

As shown in FIG. 2, washers or discs 25, 26 are provided on each side of the diaphragm and serve as a mounting for an axially movable shaft or stem 27 that is journaled in a bearing 28 fixed to the casing half 16. A coil spring 29 is interposed between the washer 26 and a sheet metal retainer ring 30 to yieldingly urge the diaphragm 19 away from the orifice 23 and force washer 25 against the wall of the casing half 15. A filter element 31 of foraminous material is clamped by the ring 30 against the wall of the casing half 16.

The shaft or stem 27 is provided with an axial opening 32 that provides communication between the chamber 22 and the outer end of the shaft 27. The outer end of the shaft 27. A flat resilient gasket 38 of cork or rubber is provided on the end of a shaft 27 and includes a base 36 and a circumferential skirt or flange 37 that surrounds the end of the shaft 27. A flat resilient gasket 38 of cork or rubber is provided on the inner surface of the base 36 and is adapted to seal against the sealing surface 34 when the cap 35 moves inwardly.

The outermost portion of the opening 32 is enlarged in diameter as at 39 and a coil compression spring 40 is interposed between a shoulder 41 that is formed in the end of the shaft 35 and the base 36 of the cap to yieldingly urge the cap 35 outwardly. To limit the outward movement of cap 35, the outer diameter of the shaft 27 is reduced adjacent the end to form a shoulder 42 and radially inwardly extending projections 43 (FIGS. 2, 3 and 4) are provided on the cap 35 which engage the shoulder 42 and limit the axial outward movement of the cap 35. It can be seen that in FIG. 4 the flanges 43 are separated by axial passages 44 that permit free communication of air as is required during normal operation. The skirt 37 functions to prevent the entry of dirt and also as a guide for the base 36 as it is moved toward the sealing surface 34 to provide a seal even under eccentric load.

When the throttle pedal is depressed and the lever 11 is moved away from the cap 35, the application of vacuum through tubing 13 and orifice 23 continuously draws air through passage 32 and between the skirt of the cap 35 through axial passage 44 and through the axial opening 32. However, when the operator lifts his foot off the throttle pedal, the lever 11 immediately returns by spring linkage forming a part of the throttle linkage to a position where it engages the cap 35. This moves the cap 35 against the action of spring 40 to bring the gasket 38 against the seat 34 of the shaft 27 as shown in FIG. 3.

Thereafter, the application of vacuum from the manifold tends to slowly evacuate the chamber 22. This evacuation is retarded primarily by the orifice 23 and secondarily by the spring 29 thereby providing a force which opposes the return of the lever 11 to a position corresponding to the throttle closed position. However, as vacuum continues, the chamber 22 is finally evacuated sufficiently to permit the diaphragm 19 and, in turn, the shaft 27 to move to the right as shown in FIGS. 2 and 3 and, in turn, permit the lever 11 and associated linkage connected to the throttle to move to the dotted line position shown in FIG. 1.

When the throttle is again depressed, the lever 11 is moved away from the end of the cap 35 permitting the spring 40 to move the cap 35 away from the end of the shaft 27. The return spring 29 then forces diaphragm 19 and shaft 27 to their original positions.

It can thus be seen that there has been provided a throttle check valve which effectively retards the closing of the throttle, which is not susceptible to dirt and the like because the valve seat is entirely protected by the flange 37 and which is relatively low in cost.

I claim:

1. A throttle check valve comprising
a casing,
piston means in the casing separating the casing into
two chambers,
an opening associated with one of said chambers for
applying a reduced pressure to said chamber,
orifice means associated with said opening,
spring means yieldingly urging said piston means away
from said opening,
a shaft connected to said piston means and extending
through said other chamber,
a passage through said shaft providing communication
between the end of said shaft and said first-mentioned chamber,
a valve seat on the end of said shaft,
a cap surrounding the end of said shaft and having a
seal thereon for engaging said valve seat,
means yieldingly urging said cap away from said valve
seat,
and means for retaining said cap on the end of said
shaft and limiting the outward movement of said cap
under the action of said yielding means.

2. The combination set forth in claim 1 wherein said cap retaining means comprises a shoulder spaced from
the end of said shaft,
and radially inwardly extending flanges on said cap
engaging said shoulder.

3. The combination set forth in claim 2 wherein said cap is made of plastic material.

4. The combination set forth in claim 2 wherein said cap is made of nylon.

5. The combination set forth in claim 1 including a filter interposed between said first-mentioned chamber and the opening through said chamber in advance of said orifice means.

6. A throttle check valve comprising
a casing,
a diaphragm dividing said casing into two chambers,
said casing having an opening in one wall communica-
ting with one said chamber,
spring means positioned in said one chamber and act-
ing on said diaphragm to yieldingly urge said dia-
phragm away from said opening,
a shaft fastened to said diaphragm and extending
through said other chamber and a wall of said casing,
said shaft having an opening therethrough providing
communication between the end of said shaft and
said first-mentioned chamber,
said shaft having a valve seat on the end thereof,
a cap surrounding the end of said shaft,
said cap having a seal adapted to engage said valve
seat,

means yieldingly urging said cap away from said seat,
interengaging means between said cap and said shaft
limiting the axial outward movement of said cap on
said shaft due to the action of said yielding means.

7. The combination set forth in claim 6 wherein said yielding means comprises a coil spring,
said shaft having an axial opening therein,
said coil spring being interposed between said cap
and the base of said axial opening in said shaft.

8. The combination set forth in claim 6 wherein said interengaging means comprises a shoulder spaced from
the end of said shaft,
and inwardly extending projections on said cap en-
gaging said shoulder.

9. The combination set forth in claim 6 wherein said cap has a continuous peripheral skirt extending axially
of said stem and surrounding the end of said stem.

10. The combination set forth in claim 6 including
orifice means associated with said opening in said wall
of said casing.

11. A throttle check valve comprising
a casing,
piston means in the casing separating the casing into
two chambers,
an opening associated with one of said chambers for
applying a reduced pressure to said chamber,
orifice means associated with said opening,
spring means yieldingly urging said piston means away
from said opening,
a shaft connected to said piston means and extending
through said other chamber,
a passage through said shaft providing communica-
tion between the end of said shaft and said first-
mentioned chamber,
a valve seat on the end of said shaft,
a cap surrounding the end of said shaft and having a
seal thereon for engaging said valve seat,
means yieldingly urging said cap away from said valve
seat,
said shaft having a shoulder spaced from the end
thereof,
said cap having radially inwardly extending flanges en-
gaging said shoulder and limiting the outward move-
ment of said cap under the action of said yielding
means.

12. A throttle check valve comprising
a sheet metal casing comprising two halves,
a diaphragm interposed between said halves and divid-
ing said casing into two chambers,
said casing having an opening in one half communi-
cating with one said chamber,
a tubular fitting mounted in said opening,
a coil spring interposed between said one half and said
diaphragm and yieldingly urging said diaphragm
away from said opening,
a bearing on said other half,
a shaft fastened to said diaphragm and extending
through said other chamber and said bearing,
said shaft having an opening therethrough providing
communication between the end of said shaft and
said first-mentioned chamber,
said shaft having a valve seat on the end thereof,
a cap surrounding the end of said shaft,
said cap having a seal adapted to engage said valve
seat,
spring means yieldingly urging said cap away from
said seal,

interengaging means between said cap and said shaft
limiting the axial outward movement of said cap on
said shaft due to the action of said yielding means.

13. The combination set forth in claim 12 wherein said spring means comprises a coil spring,
said shaft having an axial opening therein,

said coil spring being interposed between said cap and the base of said axial opening in said shaft.

14. The combination set forth in claim 12 wherein said cap has a continuous peripheral skirt extending axially of said stem and surrounding the end of said stem, said interengaging means comprises a shoulder spaced from the end of said shaft, and inwardly extending projections on said skirt of said cap engaging said shoulder.
